UNITED STATES PATENT OFFICE.

FRANK CANFIELD, OF DENVER, COLORADO, ASSIGNOR TO GEORGE B. DODGE, OF DENVER, COLORADO.

LOCKING DEVICE FOR THE CLOSURES OR STOPPERS OF JARS, BOTTLES, OR SIMILAR RECEPTACLES.

SPECIFICATION forming part of Letters Patent No. 769,816, dated September 13, 1904.

Application filed November 30, 1903. Serial No. 183,166. (No model.)

To all whom it may concern:

Be it known that I, FRANK CANFIELD, a citizen of the United States of America, residing in the city and county of Denver and State of Colorado, have invented certain new and useful Improvements in Locking Devices for the

Closures or Stoppers of Jars, Bottles, or Similar Receptacles; and I do declare the following to be a full, clear, and exact description ⁵ 10 of the invention, such as will enable others skilled in the art to which it appertains to make and use the same, reference being had to the accompanying drawings, and to the figures of reference marked thereon, which form a part ¹⁵ 15 of this specification.

My invention relates to improvements in locking devices for holding the caps, covers, closures, or stoppers of jars, bottles, and similar receptacles in place.

20 My object is to provide a device of this class which while being of simple construction shall hold the closure of the receptacle securely in place when in the locking position, but which may be readily unlocked to allow the ²⁵ 25 removal of the cap, closure, or stopper whenever it is desired to gain access to the contents of the receptacle.

The invention comprises a yoke passing over ³⁰ 30 the cap, stopper, or closure and pivotally engaging the body of the receptacle on both sides and a cam connected with the yoke and adapted to be thrown to the locked or unlocked position, as may be desired.

Having briefly outlined my improved construction, as well as the object sought to be attained thereby, I will proceed to describe the same in detail, reference being made to the accompanying drawings, in which is illustrated ³⁵ 35 an embodiment thereof.

40 In the drawings, Figure 1 is a central vertical section taken through the cap and upper portion of a jar equipped with my improved locking device. Fig. 2 is a top view of a jar equipped with the said device. Fig. 3 is a ⁴⁵ 45 side elevation of the device shown in detail and on a larger scale. Fig. 4 is a section taken on the line 4-4, Fig. 3. Fig. 5 is a sectional detail view of the cap of the jar shown in Figs. 1 and 2.

The jar shown in the drawings is supposed ⁵⁰ to be an earthen receptacle; but it must be understood that the material of which the jar is composed is immaterial so far as the application thereto of my improved device is concerned.

Referring now to the drawings, let the numeral 5 designate the body of the receptacle, and 6 the cap applied to the top thereof, a packing-ring 7 being interposed between the cap and the top of the jar. The top of the ⁶⁰ 60 cap is grooved or recessed, as shown at 8, to receive the portion 9 of my improved device. As shown in the drawings, this part 9 is bent inwardly at its lower extremity, as shown at 10, to engage a recess 12, formed in the jar. ⁶⁵ 65 This part 9 extends upwardly above the neck of the jar, and thence over the top of the cap, its extremity remote from the bearing 10 being journaled in an eccentric cam 13, as shown at 14. Surrounding this eccentric cam is an ⁷⁰ 70 eye 17, formed in the upper extremity of the locking member 15, whose lower extremity is bent inwardly, as shown at 16, to engage a recess 12^a, formed on the opposite side of the jar from the recess 12. The eccentric 13 is ⁷⁵ 75 provided with a lever-arm 13^a, having an inwardly-turned hook 13^c at its lower extremity, adapted to engage the part 15 when the cam is thrown to the locking position.

In applying the device the two hook parts ⁸⁰ 80 10 and 16 of the members 9 and 15 are made to engage the recesses 12 and 12^a, after which the part 9 is thrown upwardly over the cap 6 and into line with the recess 8 in the top of the cap, the eccentric cam in the meantime ⁸⁵ 85 being thrown to the unlocked position, or in the position when its lever-arm 13^a is raised. The lever-arm is then thrown downwardly to the position shown in the drawings, thus tightening the member 9 upon the top of the ⁹⁰ 90 jar and holding it securely in the locked position against accidental displacement.

Having thus described my invention, what I claim is—

1. A locking device for the caps, stoppers ⁹⁵ 95 or closures of jars, bottles or similar receptacles, comprising two members and a cam, the two members being pivotally connected with

the body of the receptacle on opposite sides, one of the said members extending upwardly over the closure and having its upper extremity journaled in the cam, the second member having an eye or ring formed in its upper extremity surrounding the cam which is revoluble therein, the cam being provided with a projecting part to facilitate manipulation.

2. A locking device for stoppers or closures of the class described, comprising two members respectively pivotally connected with the body of the receptacle on opposite sides, one of the said members extending upwardly over the top of the closure, and an eccentric cam connecting the two members in operative relation, substantially as described.

3. In a locking device of the class described,

the combination of a disk having a manipulating-arm, a member journaled in the body of the receptacle and extending upwardly over the cap or closure thereof, its upper extremity passing through the disk outside of its center forming the disk into an eccentric cam, and another member having an eye at one end surrounding the said cam, the other end being pivotally connected with the body of the receptacle at a point opposite the corresponding extremity of the first-named member.

In testimony whereof I affix my signature in presence of two witnesses.

FRANK CANFIELD.
